[57] CLAIM

The ornamental design for a front panel for a tape drive and autoloader, as shown and described.

DESCRIPTION

FIG. 1 is a reduced top front and right side perspective view of a front panel for a tape drive and autoloader; FIG. 2 is a front elevational view thereof;

FIG. 3 is a left side elevational view thereof;

FIG. 4 is a right side elevational view thereof;

FIG. 5 is a top plan view thereof; and,

FIG. 6 is a bottom plan view thereof.

The elements shown in broken lines in the views are for illustrative purposes only and form no part of the claimed design.

FIG. 2

FIG. 3

FIG. 4

FIG. 5

FIG. 6
